Primary Examiner — Khawaja Anwar*Assistant Examiner* — Taylor O Mortorff(74) *Attorney, Agent, or Firm* — BCF LLP(57) **CLAIM**

The ornamental design for a fabric care device as shown and described.

DESCRIPTION

FIG. 1 is a front elevation view of a fabric care device according to an embodiment of my design;

FIG. 2 is a back elevation view thereof;

FIG. 3 is a left side elevation view thereof, the right side being a mirror image of the left side;

FIG. 4 is a top plan view thereof;

FIG. 5 is a bottom plan view thereof; and,

FIG. 6 is a perspective view taken from a front, left side thereof.

Throughout the Figures, where shown, the dashed lines are included for the purpose of illustrating portions of the fabric care device which form no part of the claimed design.

1 Claim, 3 Drawing Sheets
